UNITED STATES PATENT OFFICE.

PAUL STUCKER, OF BROOKLYN, NEW YORK.

DESIGN FOR A WATCH-CASE.

SPECIFICATION forming part of Design No. 17,104, dated February 8, 1887

Application filed October 12, 1886. Serial No. 217,591. Term of patent 10 years.

To all whom it may concern:

Be it known that I, PAUL STUCKER, of Brooklyn, in the county of Kings and State of New York, have invented and produced a new and original Design for Watch-Cases or Lockets, of which the following is a specification, reference being had to the accompanying drawings, forming a part thereof, in which—

Figure 1 represents a face view of my newly-designed watch-case, and Fig. 2 is a cross sectional view on the line $x x$ of Fig. 1.

The leading feature of the present design consists of a case wherein one section is scalloped, while another section is bassine, these two sections being preferably defined by an ornamental band, as illustrated.

In the drawings, A represents the scalloped section, the scallops extending across the periphery of the case, B the plain or bassine section, and C the ornamental band between the two sections, the scalloped section A and the band C being engraved in any manner desired.

I use the word "bassine" as the same is used in the trade—viz., to designate a watch in which the edge of the case is rounded.

Having thus fully described my invention, I claim as new and desire to secure by Letters Patent—

1. The design for a watch-case herein shown and described, the same consisting in a transversely-divided case, one section of which is plain and the other scalloped, as set forth.

2. The design for a watch-case herein shown and described, the same consisting of the upper plain section of bassine contour and the lower scalloped section, as set forth.

3. The design for a watch-case herein shown and described, the same consisting of a scalloped and a bassine section that are defined by an intermediate ornamental band, substantially as described.

4. The design for a watch-case herein shown and described, the same consisting of a plain section and an engraved peripherally-scalloped section, the two sections being defined by an ornamental band.

PAUL STUCKER.
